UNITED STATES PATENT OFFICE

2,046,405

MACHINE FOR EDGING GLASS SHEETS

William Owen, Pittsburgh, Pa., assignor to Pittsburgh Plate Glass Company, a corporation of Pennsylvania

Application May 31, 1935, Serial No. 24,383

9 Claims. (Cl. 51—103)

The invention relates to apparatus for grinding the edges of glass sheets ordinarily to give them the half round or pencil edge required for automobile glass, and the apparatus herein shown and described constitutes an improvement on the apparatus of my application for patent, Serial No. 7,824, filed February 23, 1935. The invention is illustrated as applied to plates or sheets of safety glass consisting of two sheets of glass cemented to an interposed sheet of celluloid or the like, but the machine is equally well adapted for grinding the edges of sheets of ordinary plate glass and for edging sheets designed for service other than as automobile glass. The invention has for its principal objects the provision of a machine of the general type shown in my application above referred to having improved means for maintaining the sheets in grinding engagement with the grinding wheel and steadyng them, and the provision of means whereby the sheets may be ground in matched pairs, thus increasing the capacity of the machine and avoiding the concentration of grinding pressure on those corners of the sheet which are relatively sharp, which tends to cause breakage of such corners when such expedient is not employed. A further object is the simplification and cheapening of the apparatus of my previous application. Certain embodiments of the invention are illustrated in the accompanying drawings, wherein:

Figure 1 is a side elevation of the machine. Fig. 2 is an end elevation. Fig. 3 is a section on the line III—III of Fig. 1, but with the glass plates rotated 90 degrees from the position shown in Fig. 1. Figs. 4, 5 and 6 are detail views. And Figs. 7 and 8 are side elevations showing two modifications.

Referring to the drawings, the framework of the machine shown in Figs. 1 and 2 comprises a pair of channels 1, 1, pairs of uprights 3, 3 and 4, 4, and a transverse top section consisting of the angles 5 and 6, the frame members being suitably secured together in a rigid framework by means of bolts or rivets. A closure member 7 preferably of light metal prevents water from being thrown to the left (Fig. 1) during the grinding operation, the water being supplied to the grinding wheel by means of the spray pipes 8, 8. A grooved edging or grinding wheel 9 is suitably mounted in the upper portion of the framework upon the shaft of the electric motor 10. As in the construction of my application heretofore referred to, the plates to be edged are carried in a loop 11 of the belt member 12, such loop being located beneath the grinding wheel and forced

upward by suitable means so as to secure the necessary grinding pressure between the edges of the glass plates and the grinding wheel. The belt 12 is preferably in the form of a sprocket chain of the construction indicated in Figs. 3 and 5, such chain passing around the sprockets 13, 14, 15, 16 and 17. The sprockets 15 and 16 are mounted in fixed position upon the transverse frame member 6, a plurality of holes for the shafts of the sprockets being provided to permit of adjustment in the position of the sprockets. The sprocket 14 provides the drive for the chain, being keyed to the shaft of the electric motor 18, which is bolted to the upright frame members 3. The sprocket 13 acts as a tensioning means for the chain and assists in pulling the loop 11 upward toward the grinding wheel. This sprocket is mounted upon the lever arm 19 pivoted at 20 to a bracket 21 secured to the upper ends of the frame members 3 and 4. The lever arm is counterweighted by means of the weight 22 which is adjustable longitudinally of the lever by means of the screw 23. A spring 24 secured at one end to the lever arm and at the other end to a bracket 25 supplements the action of the counterweight.

In operation, the grinding wheel 9 and the work which is carried by the loop 11 are rotated in a counterclockwise direction, as indicated by the arrows, and the force which is thus applied to the edge of the work tends to swing the work to the right. This tendency is counteracted and the work is steadied by means of a sprocket 26 carried upon the bracket 27, such bracket being adjustable in a horizontal direction by means of the bolt and slot connection with the frame members 3, 4, as indicated at 28 and 30. In order to supplement the action of the lever 19 in pulling the loop 11 upward and thus give the necessary grinding pressure between the edge of the work and the grinding wheel, a lever 31 is provided carrying at one end the sprocket wheel 32 engaging the chain and having at the other end the weight 33. The engagement of this sprocket wheel with the chain also serves to steady the work. The sprockets 26 and 32 also tend to prevent the work from swinging laterally out of the plane of the grinding wheel.

The chain which is employed is preferably of the roller type indicated in Fig. 5, in which the side bars 34 of alternate links are provided with wings 35 which serve to support the continuous grooved rubber strips 36 and 37, in which the edges of the glass sheets fit, the strips being secured to the wings by means of the rivets 38. The strips are coextensive in length with the

chain and give a secure support for the edges of the glass sheets, their flanges serving to prevent any lateral movement of such edges so that the glass sheets are securely maintained in alignment with the grooves 39 in the grinding wheel.

As will be seen by reference to Figs. 1 and 3, the arrangement permits of the grinding of the edges of four similar sheets of glass at one time. The sheets 40 and 41 are, in the present instance, side lights which are of greater length than width with the longest sides of the plates in opposition and secured in such position by means of suitable clamping means. This clamping means preferably comprises the central strip 42 and the two side strips 43 and 44 having the cross section indicated in Fig. 3 and secured in assembled relation by means of a pair of bolts 45 carrying the wing nuts 46 at one end. This arrangement of grinding the sheets in pairs increases the capacity of the machine and renders the operation more satisfactory than is the case where the sheets are not placed edge to edge, since by this expedient the application of the grinding wheel to sharp corners on the plates is avoided and breakage is reduced. As shown, each of the plates or sheets consists of a pair of glass sheets 47, 47 with an interposed sheet 48 of reinforcing material, such as cellulose nitrate plastic. In edging a plate of this kind, there is a tendency to accumulate some of the plastic in the grooves of the grinding wheel and interfere with its operation, and in order to keep these grooves clean, scraping devices may be employed, as indicated in Fig. 4. As here shown, the strip 42 is provided at its end with longitudinal recesses in which strips of glass 49, 49 are mounted, such strips being backed up by springs 49a. In operation these glass strips scrape the grooves in the grinding wheel when the work reaches the position indicated in Fig. 1, thus tending to keep the grooves clear from an accumulation of plastic.

Fig. 7 illustrates a modification wherein the loop 50 of the belt which carries the work is pressed upward into engagement with the grinding wheel 51 by means of the pair of sprockets 52, 52 carried upon an arm 52a. This arm is pivotally mounted at 53 upon a lever 53a counterweighted by means of the weight 54. The chain is tensioned in this instance by means of the 50 counterweighted lever 54a having a sprocket 55 around which the chain passes. The chain is here driven from the sprocket 56 which is carried upon the shaft of the motor 56a. The chain is guided in this case by three additional sprockets 57, 57a and 58, suitably supported upon the framework 58a of the machine.

Fig. 8 illustrates a modification in which the edging is accomplished by a pair of grinding wheels 59 and 60 mounted in the frame 61 and 60 suitably driven by motors 59a and 60a. The loop 62 which carries the work is pressed upward by sprockets 63 and 64 carried upon the counterweighted levers 65 and 66. The chain is preferably tensioned by means of the sprocket 67 carried upon the lever arms 68, such lever arm being keyed to the shaft 69 which carries the counterweighted lever 70. Other sprocket wheels 71, 72, 73, 74 and 75 are employed for suitably guiding the chain. The chain is driven by the 70 motor 76, on whose shaft is mounted a sprocket 77 over which the chain passes.

What I claim is:

1. A glass plate edging machine comprising a driven grooved grinding wheel having a horizontal axis, an endless driven belt lying in the same

plane as the wheel and having a loop below the wheel partially surrounding the glass plate to be edged, means for tensioning the belt, and rotating means engaging the lower portion of said loop and yieldingly pressing the loop and glass plate carried thereby upward to secure grinding pressure of the edge of such plate upon the grinding wheel, the belt being provided with flanges lying on each side of the glass plate for holding it in the plane of rotation of the grinding wheel. 10

2. A glass plate edging machine comprising a driven grooved grinding wheel having a horizontal axis, an endless driven belt in the form of a sprocket chain lying in the same plane as the wheel and having a loop below the wheel partially surrounding the glass plate to be edged, means for tensioning the chain, and a sprocket engaging the loop portion of the chain and yieldingly pressed upward to cause grinding pressure between the edge of the glass plate and the grinding wheel, the chain being provided with flanges lying on each side of the glass plate for holding it in the plane of rotation of the wheel. 20

3. A glass plate edging machine comprising a driven grooved grinding wheel having a horizontal axis, an endless driven belt lying in the same plane as the wheel and having a loop below the wheel partially surrounding the glass plate to be edged, means for tensioning the belt, a steady wheel at one side of the loop to prevent such loop from being swung laterally due to the grinding engagement between the grinding wheel and the glass sheet, and a wheel engaging the lower portion of the loop and yieldingly pressed upward to secure grinding pressure between the grinding wheel and the edge of the glass plate, the belt being provided with flanges lying on each side of the glass plate for holding it in the plane of rotation of the grinding wheel. 30

4. A glass plate edging machine comprising a driven grooved grinding wheel having a horizontal axis, an endless driven belt lying in the same plane as the wheel and having a loop below the wheel partially surrounding the glass plate to be edged, a wheel located above the axis of rotation of the grinding wheel over which the belt passes yieldingly pressed upward for tensioning the belt, and rotating means engaging the lower portion of said loop and yieldingly pressing the loop and glass plate carried thereby upward to secure grinding pressure of the edge of such plate upon the grinding wheel, the belt being provided with flanges lying on each side of the glass plate for holding it in the plane of rotation of the grinding wheel. 45

5. A glass plate edging machine comprising a driven grooved grinding wheel having a horizontal axis, an endless belt lying in the same plane as the wheel and having a loop below the wheel partially surrounding the glass plate to be edged, an idler wheel located above the axis of rotation of the grinding wheel over which the belt passes yieldingly pressed upward for tensioning the belt, yielding means engaging the lower portion of said loop and pressing the loop and glass plate upward to secure grinding pressure of the plate upon the grinding wheel, and driving means for the belt intermediate the idler wheel and said loop, the belt being provided with flanges lying on each side of the glass plate for holding it in the plane of rotation of the grinding wheel. 60

6. A glass plate edging machine comprising a driven grooved grinding wheel having a horizontal axis, an endless driven belt lying in the same

same plane as the wheel and having a loop below the wheel partially surrounding the glass plate to be edged, means for tensioning the belt, and a pair of spaced wheels engaging the lower portion of said loop and yieldingly pressed upward to secure grinding pressure between the grinding wheel and the edge of the glass sheet, the belt being provided with flanges lying on each side of the glass plate for holding it in the plane of rotation of the grinding wheel.

7. A glass plate edging machine comprising a driven grooved grinding wheel having a horizontal axis, an endless driven belt lying in the same plane as the wheel and having a loop below the wheel partially surrounding the member to be edged, a clamp securing together the opposing long edges to two similar glass plates of greater length than width which together constitute the member to be edged, and means engaging the belt and tending to move the loop upward so that the edge of said member is yieldingly held in engagement with the grinding wheel, the belt being provided with flanges lying on each side of said member for holding it in the plane of rotation of the grinding wheel.

8. A glass plate edging machine comprising a driven grooved grinding wheel having a horizontal axis, an endless driven belt lying in the same plane as the wheel and having a loop below

the wheel partially surrounding the member to be edged, a clamp securing together the opposing long edges to two similar glass plates of greater length than width which together constitute the member to be edged, a scraper of hard material mounted in the end of the clamp for movement longitudinally thereof and yieldingly pressed outward, and means engaging the belt and tending to move the loop upward so that the edge of said member is yieldingly held in engagement with the grinding wheel, the belt being provided with flanges lying on each side of said member for holding it in the plane of rotation of the grinding wheel.

9. A glass plate edging machine comprising a driven grinding wheel having a horizontal axis and provided with a pair of peripheral grooves, an endless driven belt lying in the same plane as the wheel and having a loop below the wheel arranged to partially surround the glass plates to be edged, said belt comprising a sprocket chain with a continuous grooved rubber strip secured to each side thereof adapted to carry one of the glass plates, and means for tensioning the chain and causing the loop to maintain the sheets carried by the rubber strips in grinding engagement with the grooves in the wheel.

WILLIAM OWEN.
